BLADE STRUCTURE FOR AIRCRAFT SUSTAINING ROTORS

Filed Feb. 19, 1942

UNITED STATES PATENT OFFICE

2,388,879

BLADE STRUCTURE FOR AIRCRAFT
SUSTAINING ROTORSPaul H. Stanley, Huntingdon Valley, Pa., assignor
to Autogiro Company of America, Philadelphia,
Pa., a corporation of Delaware

Application February 19, 1942, Serial No. 431,470

3 Claims. (Cl. 244—18)

This invention relates to aircraft sustaining rotor blades.

The invention, moreover, is especially concerned with a molded blade in which a body of expanded or cellular and resilient material, such as sponge rubber, is molded to define the airfoil contour of the blade, the body of said material having embedded therein a reinforcing structural skeleton of novel form, as is more fully described hereinafter.

One of the general objects of the invention is to simplify the structure and fabrication of a blade of this type, in order to make practicable manufacture of rotor blades from molded cellular material.

More specifically, the invention has in view the provision of means, especially structural elements, arranged to provide effective strength and reinforcement, notwithstanding the formation of the blade from relatively light cellular material, such as expanded or sponge rubber.

In accordance with another aspect of the invention, the structural skeleton of the blade is arranged in a novel manner not only achieving the foregoing purposes but, at the same time, maintaining a desirable cross sectional weight balance in the blade, this being of importance for dynamic and aerodynamic reasons which need not be considered in detail herein.

How the foregoing and other objects and advantages are attained will appear more fully from the following description, referring to the accompanying drawing, in which—

Figure 1 is a somewhat diagrammatic plan view of a blade constructed in accordance with this invention, an intermediate portion of the blade being broken out, and certain parts being shown in horizontal section;

Figure 2 is a sectional view taken on the line 2—2 of Figure 1;

Figure 3 is a fragmentary horizontal sectional view of the nose portion of the blade, this view illustrating a short piece of the spar in plan; and

Figure 4 is an elevational view of one of the rib elements employed in the structural skeleton.

The primary longitudinal strength structure of the blade comprises a tubular spar 5 extended substantially throughout the entire length of the blade and having a root end fitting 6 at its inboard end, the fitting being provided with an apertured lug 7 adapted to cooperate with a blade mounting pivot by means of which the blade may be secured to the rotative hub. Lug 55

1 may serve for cooperation with a "drag" pivot, but the blade mounting preferably also includes a "flapping" pivot (not shown) the flapping pivot providing freedom for swinging movement of the blade in a direction generally transverse its mean rotative path of travel.

It may be mentioned that the blade, as broken out in Figure 1, is greatly shortened as compared with the usual plan form, in accordance with which the blade length is commonly equal to from twelve to fifteen times the chord dimension.

At spaced intervals along the spar partial ribs 8 are provided, each of these ribs preferably having a foot 9 or the like adjacent the nose of the blade and adapted to cooperate with a nose strip 10, said strip being secured to the ribs, as by welding. As seen in Figure 2, the sectional shape of the nose strip 10 is such as to define a portion of the airfoil contour of the nose of the blade.

In accordance with the invention, the blade is built up by placing the skeleton strength structure described above in a suitable mold and then introducing the molding material in a fluid or plastic state, the entire blade thus being molded as a unit, with the structural skeleton embedded therein. A best seen in Figure 2, the contour of the molded material toward the nose of the blade constitutes a continuation of the nose contour provided by the strip 10.

Known processes for curing or vulcanizing the plastic material may be employed, so as to produce an integral structure reinforced by the spar, ribs 8 and nose piece 10. By the employment of cellular or expanded molding material, a relatively lightweight blade may be obtained, which blade, however, further has considerable strength because of the structural skeleton embedded therein. In this connection, it is pointed out that the ribs 8 not only project forwardly of the spar so as to support the nose strip, but also project rearwardly so as to effectively carry the centrifugal load set up during rotation and transmit the same from the molded material to the spar.

Examination of the drawing will further show that each of the ribs 8 is not only provided with apertures 11, but is further flanged around the periphery, as indicated at 12, to provide surfaces 50 which, when projected on the mean plane of the blade, are of appreciably extended area. In this way, embedding of these ribs in the molded material effectively secures the body of the blade to the spar as against torsional dislodgment about the axis of the spar.

Referring further to the nose strip 10, it is pointed out that the arrangement thereof as herein disclosed is of particular advantage since the strip serves as an effective protection for the nose of the blade (which is of importance in preventing damage), and at the same time said strip further is highly effective in ballasting the blade to maintain the desired forward location of the sectional center of gravity. Since the strip 10 is at the forwardmost point of the cross sectional contour, the ballasting may be achieved with a minimum of weight.

Although the material of which the blade is molded may be of a variety of different types, varying in elasticity, resilience and porosity, preferably the material is considerably expanded (having considerable voids) and, additionally, has at least that degree of resilience which will avoid damage to the blade under the influence of the normal flexing which takes place in operation.

I claim:

1. For an aircraft sustaining rotor, a substantially elongated aeroform blade comprising a single main spar extending along the major axis of the blade and having a pivotal connection device at its root end so that the entire centrifugal load of the blade is carried through the root end of said single spar, molded material surrounding the spar and in large part defining the aerofoil contour, a tough leading edge strip of channel

form running along and substantially defining the nose of the aerofoil substantially throughout the length of the molded material, and a plurality of transverse members secured to the spar at intervals therealong, extending forwardly within said molded material and secured to said leading edge strip and transferring the centrifugal load on said strip to said spar, while forming with said spar and strip a unified structure for supporting and retaining the molded material and for stiffening the blade as against bending in the mean plane thereof to an appreciable greater extent than in the flapping direction.

2. A construction according to claim 1, wherein said transverse members are of generally plate-like formation from the spar to the leading edge strip and flanged at the points of connection to the spar and the strip, said leading edge strip being of relatively heavy material as compared to said molded material, thereby bringing the sectional center of gravity of the blade forward to the desired location.

3. A construction according to claim 1 in which said transverse members have laterally projecting flanges embedded in the molded material and serving to reinforce the molded material as against torsional deformation about the axis of the spar.
